(57) CLAIM

The ornamental design for a scarf, as shown and described.

DESCRIPTION

FIG. 1 is a perspective view of a scarf embodying my new ornamental design;

FIG. 2 is a front view of said scarf;

FIG. 3 is a back view of said scarf;

FIG. 4 is one side view of said scarf;

FIG. 5 is another side view of said scarf;

FIG. 6 is a top view of said scarf; and,

FIG. 7 is a second embodiment of a scarf showing my new design, the only difference being the straight bottom edge.
